UNITED STATES PATENT OFFICE

WALTER A. HEINRICH, OF ST. LOUIS, MISSOURI, ASSIGNOR TO W. N. MATTHEWS CORPORATION, OF ST. LOUIS, MISSOURI, A CORPORATION OF MISSOURI

SWITCH

Application filed January 25, 1926. Serial No. 83,530.

This invention relates to electrical distribution apparatus and particularly to fuse switches and their containing boxes such as are used in high potential transmission lines.

5 The general type of switch box involved is shown in prior Patents, No. 1,288,951 and No. 1,398,335, issued to Claude L. Matthews and myself, December 24, 1918, and November 29, 1921, respectively.

10 The general type of fuse switch involved is shown in prior Patent No. 1,514,210, issued to myself November 4, 1924.

15 Among the several objects of my present invention may be noted the provision of an improved combination of parts whereby positive operation of the switch may be had without jamming of parts and yet whereby more or less loose fits may be employed between certain removable elements which have a tendency, when made up with the ordinarily required accurate fits, to swell and stick, or corrode and stick, so that quick manual removal is impossible. The present invention permits ready removal and insertion of these certain parts under adverse service conditions, that is, without the application of excessive force or the requirement of an accurate manipulation. Other objects will appear in part and will in part be pointed out hereinafter.

20 The invention accordingly comprises the features of construction, combinations of elements and arrangements of parts, which are exemplified in the description hereinafter in connection with the accompanying drawings, and the scope of the application of which will be indicated in the following claims.

25 In the accompanying drawings, in which is illustrated one of various possible embodiments of the invention,

30 Fig. 1 is a vertical section taken from front to rear of the fuse box, showing certain parts in elevation, and in dotted lines alternate positions of certain parts, a clip block being shown in lowered position;

35 Fig. 2 is a vertical section taken on line 2—2 of Fig. 1, the lid being shown open, the clip block in raised, connected position, and the fuse block removed;

40 Fig. 3 is a longitudinal section of the fuse block; and,

Fig. 4 is a bottom plan view of the switch box as a whole showing it closed and in connected position.

Similar reference characters indicate similar parts throughout the several views of the drawings.

Referring now more particularly to Figs. 1 and 2, there is illustrated at 1 the back of the switch box. Sides 3 are made fast to the back 55 1. The upper edges of the sides slope rearwardly and a rearwardly sloping waterproof cover 5 is screwed to the top edges of the back sides. The cover 5 overhangs the box at all points to form eaves. It comprises a preferably wooden piece 6 covered by a copper or other non-corroding sheet of material 8. The sheet 8 is turned under at the edges of the cover. A partially open bottom portion 7 is formed in the box.

60 On the sides 3 beneath the eaves of the cover 5 are screwed forwardly extending purchase pieces 9. These extend forwardly past and flush with a front door 11. The door 11 has screwed to its edges vertical purchase pieces 13, crimped to accommodate the passage of 65 said pieces 9. The pairs of pieces 9 and 13 intersect one another in side elevation and at the point of intersection are provided with holes drilled in line. A set of drive screws 17 are horizontally passed through the pairs 70 of holes and into the door 11 whereby the door 11 is ruggedly and economically hinged to the said box at the top front edge thereof. The improved purchase on the box of the hinges, 75 formed as described, is evident.

80 The door 11 swings forwardly on the hinge pieces and at its lower end is provided with an inwardly extending portion 15 of said bottom 7 (see Fig. 4). The portions 7 and 15 of the bottom cooperate when the door 11 is 85 closed to close the lower end of the box except at an open slot 19. This slot 19 permits the lower open end 21 of a fuse block 23 to protrude from the box for purposes to be described. The slot is cut partially in the piece 90 7 and partially in the piece 15.

85 A clip 25 serves to hold the door 11 normally closed. It comprises a U-shaped piece of 95 spring metal screwed to the door and having sideward legs 18. The legs 18 are provided 100

with holes 20 which yieldingly engage the heads of screws 22 placed in the sides 3 of the box.

To hold the door in open position while the fuse carrying member 23 is being removed or replaced or other operations performed, there is provided a spring detent member 27, one end of which is pivotally connected to a suitable bracket 29 on the door 11 (Fig. 1).

10 This detent member 27 is provided with a slot 31 through which passes a pin or stud 33, the same being seated in the end of the side walls 3. The inner end of this detent is rebent to form a spring finger 35, the end of 15 which bears against the inner face of said detent 27, and thus when the door is swung into open position, as shown by dotted lines in Fig. 1, the head of the stud 33 will ride into position beneath the spring finger as shown 20 in Fig. 2, and thus the door will be yieldingly restrained in open position.

The box as a whole is held in position by brackets 37 fastened to the back 1.

Within the box are provided several novel 25 features for making quick connections to a clip block and fuse block.

On the back 1, within the box is provided an adjustable clip block 39. This block is provided with slots 41 for the loose passage therethrough of bolts 43. The bolts pass through holes in the back 1 of the box and are provided on the outside with washers and nuts. The heads of the bolts 43 are larger than the slots 41, and hence by tightening the 35 nuts may be caused to clamp the clip block against the back 1 of the box. Likewise loosening of the nut will permit the clip block 39 to be adjusted vertically.

The clip block 39 comprises the relatively 40 thin bar into which said slots 41 are cut. It carries at each end a clip insulator 45.

At the upper end of the insulators 45 are molded in U-shaped clip assemblies 51. These form switch terminals. Fastened to 45 said assemblies or terminals 51 are terminal wire connectors 63 located angularly with regard to the vertical center line of the box. The connectors 63 are adapted to receive wire ends therein and are provided with set screws for holding the wires. Between the inner 50 open ends of the pairs of hollow connectors 63 are cast two solder troughs 65 separated from one another by a wall 67. By this means either or both of two wires brought 55 into a pair of connectors 63 may readily be soldered after fastening has been accomplished by means of the screws.

The clip block 39 carries an insulator assembly at each end thereof. It is evident 60 that the clip block carrying the insulator assemblies may be moved vertically into any of various positions. The purpose of this is as follows:

When leading wires into the switch box it 65 is necessary to provide ample insulation there-

for. Hence the sides 3 of the box are drilled in a slanting fashion as shown in Fig. 2 at the numerals 69. These holes 69 are adapted to receive cylindrical insulators 71 from the inside of the box. The insulators 71 are provided with shoulders 73 which prevent their sliding out of the box, and they are pointed downwardly to prevent moisture from entering the box.

The parts of this device are so arranged 75 that when the clip block assembly 39 is in its lowermost position (Fig. 1), the insulator and the clip assemblies 51 do not interfere with the entering of the insulator tubes 71 into their respective holes 69. However after 80 the insulator tubes 71 have been entered into their respective holes 69 the clip block and all that it carries may be slid upwardly to the position shown in Fig. 2, whereupon the wire terminal pieces 63 are aligned with the centers 85 of the bore of the insulators 71. After positioning the clip block, as described, the nuts of bolts 43 may be tightened to hold said block in its proper position. In Fig. 1 the fuse-carrying member 23 is shown in position 90 for convenience of illustration.

After alignment between terminals 63 and insulators 71 is attained as shown in Fig. 2, wires 75 may be pushed through the insulators 71 directly into the wire terminals 63 and the 95 ends put into troughs 65 without bending or crimping the wire. Solder may then be applied to the wire and into one of the troughs 65 thereby making an excellent electrical connection.

Referring now to Fig. 3, the fuse carrying member or switch 23 will be described.

It comprises two, preferably fibre, insulating tubes held together by a lower band 77, and a central band and metallic terminal piece 105 79. At the upper end of the longer of the two tubes, namely tube 81, is provided another metallic terminal piece 83. The terminal pieces 79 and 83 are adapted to receive in electrical connection therewith a fuse wire 110 85. The ends of the wire are clamped to the insides of the terminal pieces 79 and 83 by means of set screws 87. Hence it is evident 115 that the fuse wire may be removed from the tubes merely by loosening the set screws 87 and withdrawing it from the open lower ends of the tubes. The fuse terminals 79 and 83 of the fuse or switch 23 are adapted to resiliently co-operate with the clip assemblies or 120 terminals 51 if positioned between the side-ward spring legs 89 of said U-shaped assemblies 51. In order to facilitate placement of the fuse block a clamp 88 is made fast to the lower insulator assembly 45. This clamp is provided with a downward extension 91. 125 Forwardly positioned legs 93 and 95 are formed with the extension 91. The lower leg 93 has a pivot 97 formed therewith at a point substantially in line with the flat base portions 99 of the U-shaped clips 51. The pivot 130

97 rotatably carries a girth strap 101 adapted to loosely surround the lower end 21 of the fuse block. The strap 101 forms a loose socket which might be made in different ways.

By thrusting the lower end 21 of the fuse 5 block 23 into the strap or socket 101, it will be automatically positioned for insertion of the terminals 79 and 83 into the clips 51. The band 77 serves to position the block vertically. Said band 77 positions itself under the 10 arm 95, the play at the strap 101 permitting such placement.

Then by swinging the fuse carrying member 23 with the strap 101 vertically, the terminal pieces 79 and 83 of the member 23 15 are thrown into contact with the clips 51 and hence electrical connection is made between the respective clips on the insulators. These clips are the line terminals, as described, and are now connected by means of the fuse wire 20 85.

It may be seen that the loose connection between the fibre tubes 81 and 82 of the fuse block 23 and the strap or socket 101 is provided in order that, not only may the block 25 be readily thrust into said strap 101, but also that swelling or corroding of the tubes of the block will not cause the block to be wedged into said strap 101 or like member. Such wedging action causes much trouble for the 30 linemen in that a blown fuse thus jammed or stuck can only be removed at the expense of a disassembly of certain parts or a breakage of parts. The relatively inaccessible positions generally occupied by these line 35 switches multiply the difficulties.

Heretofore initially snug fits were necessary between members such as member 101 and the tubes of the preferably fibre fuse block. This was because more or less perfect 40 alignment was needed between the swinging fuse block 23 and the clips 51 when the pivot 97 was located an appreciable distance below the line of the clip bases 99. Under the described previous pivoting conditions, the terminals 79 and 83 of the fuse block 23 were 45 caused to enter the spring legs 89 of the clips 51 with a large component of motion directly into the lower unrounded edges 103. It was therefore necessary to provide good alignment and therefore a tight fit at a member such as member 101, in order that looseness 50 would not cause jamming or interference at said unrounded clip edges 103. The tight fit caused the difficulties due to swelling of the 55 fibre as hereinbefore noted.

The present positioning of the pivot 97 almost entirely eliminates said large component of motion directly into the unrounded edges 103. The fit at the strap 101 may then 60 be made loose because accurate positioning of the terminals 79 and 83 need not be had in order to place them into clips 51 substantially from the rounded top edges 105.

The purpose of the arm or leg 95 is to prevent 65 a rocketing motion of the fuse block 23

out of the clips 51 when the fuse blows and thereby exhausts gases and the like downwardly out of the box. The members 77, 79 and 83 are all tightly formed with the tubes 81 and 82.

It is evident from the above that a fuse 70 block 23 may at any time be readily put into or taken from a box with little time or trouble being involved in unwedging blocks or nicely manipulating a block to align with its terminal clips 51. The unit 23 may comprise an ordinary switch bar without a fuse 75 therein. Such bars and the described fuse assembly are interchangeable.

In order to make the device safe for operation by a lineman, a bridge portion 107 80 is cast with the upper terminal piece 83 which may be engaged by a hook of an insulated tool carried by the lineman, whereby he is not required to apply his bare hands to the fuse carrying member 23, either for engagement or disengagement thereof. The improvements above set forth are of increased value where it is needful to use such a safety tool as described, because less accurate control is had of the block 23 with the tool than 85 with the hands.

It should be understood that although four 90 holes 69 are shown in the accompanying drawings for the use of four insulators 71 and four lead-in wires, that only two insulators 95 71 are shown, although four of them might be used if desired.

From the above it will be seen that the several objects of the invention are attained and other advantageous results achieved.

As many modifications of the embodiments above illustrated might be made without departing from the spirit or scope of the present invention, it is intended that the above description and accompanying drawings and claims shall be interpreted as illustrative and not in a limiting sense.

I claim:

1. A fused switch comprising a box, an insulator block assembly therein carrying terminals, a fuse block adapted to electrically connect the terminals, a clamp fastened to said assembly, a socket pivoted to said clamp, said pivot being substantially aligned with said terminals, the socket being adapted to loosely receive the fuse block, and a lug fastened to said clamp adapted to prevent movement of the fuse block from the terminals when the fuse blows.

2. A fused switch comprising a box, an insulator block assembly therein carrying U-shaped fuse terminals, a fuse block adapted to electrically connect the terminals, a clamp fastened to said assembly, a socket pivoted to said clamp, said pivot being substantially aligned with the base portion of said terminals, the socket being adapted to loosely receive one end of the fuse block, and a lug fastened to said clamp adapted to prevent 120 125 130 movement of the fuse block from the terminals when the fuse blows.

movement of the fuse block from the terminals when the fuse blows.

3. A switch comprising a box, terminal-carrying means therein, terminals therefor, means adapted to electrically connect the terminals, and means fastened to said terminal-carrying means having a socket pivoted thereto, said socket being adapted to removably receive said connecting means, said socket being positioned below the lowest of said terminals.

4. A switch comprising a box, an adjustable terminal-carrying assembly therein, terminals therefor, connecting means for said terminals, means fastened to said assembly having a socket pivoted thereto, said socket being adapted to removably receive said connecting means, said socket being positioned below the lowest of said terminals, and a member fastened to said fastened means adapted to prevent longitudinal movement of the connecting means when said connecting means is in connecting position.

5. A switch comprising a support, terminal carrying means thereon, terminals therefor, means adapted to electrically connect said terminals, means fastened to the terminal carrying means having a socket swingable thereon, said socket being adapted to removably receive said electrical connecting means, said socket being positioned below the lowest of said terminals.

In testimony whereof, I have signed my name to this specification this 20th day of January, 1926.

WALTER A. HEINRICH.
